STUCCOING AND PLASTERING MACHINE

Application filed December 22, 1928. Serial No. 327,842.

The invention relates to means adapted to regulate the distance the carriage of said device may travel vertically.

The objects of the invention are to provide simple, efficient, and practical means whereby said plastering machine may be quickly and conveniently adjusted dependent upon the height of the walls, or other vertical surface, to which plastic material is to be applied.

The invention consists in the combination of the parts, in the detail of the construction, and in the arrangement of the elements, as claimed.

15 In the drawings:

Fig. 1 is a side elevation of the invention, with parts broken away;

Fig. 2 is a section taken on a line corresponding to 2—2 in Fig. 1;

20 Fig. 3 is a vertical section taken on a line corresponding to 3—3 in Fig. 2;

Fig. 4 is a vertical section taken on a line corresponding to 4—4 in Fig. 2;

Fig. 5 is a section taken on a line corresponding to 5—5 in Fig. 1;

Fig. 6 is a section taken on a line corresponding to 6—6 in Fig. 1;

Fig. 7 is a plan view of the invention;

Fig. 8 is a section taken on a line corresponding to 8—8 in Fig. 1;

Fig. 9 is a section taken on a line corresponding to 9—9 in Fig. 8;

Fig. 10 is a section taken on a line corresponding to 10—10 in Fig. 5.

35 Fig. 11 is a section taken on a line corresponding to 11—11 in Fig. 7.

Fig. 12 is a section taken on a line corresponding to 12—12 in Fig. 5.

In the preferred construction of the invention, I provide the plastering machine 1 having the frame 2 comprising the spaced apart rectangular vertical supports 3, the base plate 4, the top plate 5 and the telescopic upper tubes or supports 6 slidably mounted in the holes 7 in the upper ends 8 of the lower tubes or supports 3. The lower ends 9 and the upper ends 10 of the supports 3 are received on the lugs in the base plate 4 and the top plate 5 respectively and secured thereto in any suitable manner.

Slidably mounted on the supports 3 is the carriage 11. The frame 12 of the carriage comprises the spaced apart sides 13 and 14 each having the spaced apart rectangular holes 15 and 16 therein slidably receiving the supports 3. The sides 13 and 14 are maintained in fixed relation with respect to each other as by the spaced apart and parallel horizontal struts 17, 18 and 19, extending intermediate the sides 13 and 14 and integral therewith.

Intermediate the holes 15 in the side 13 of the frame 12 is the integral hub 20 slidably receiving the lower vertical screw 21 having its lower end 22 journaled in a suitable bearing in the base plate 4. Intermediate the holes 16 in the side 14 of the frame 12 is the integral internal threaded hub 23 threaded to the upper vertical screw 24 having its lower end 25 journaled in a suitable bearing in the base plate 4.

The usual electric motor 26 is mounted upon the base plate 4, and is operated by suitable outside source of electric source of supply. On the driving shaft 27 of the motor 26 is suitably fixed the sprocket 28.

For the purpose of providing means whereby the carriage 11 may be operated at variable speeds upwardly and at one speed downwardly, the usual transmission box 29 mounted upon a base integral with the top of the motor 26, has on its input shaft 30 the gear 31 meshing with the gear 32 secured to the horizontal shaft 33 rotatably mounted in suitable bearings in the bosses 34 integral with the motor 26.

The transmission is usual construction adapted to effect two different speeds of the output shaft 35 in one direction and one speed of the output shaft 35 in a reverse direction. 90 Fixed to the end 36 of the shaft 33 is the sprocket 37 rotated by the belt chain 38 operatively connected with the sprocket 28, whereby the output shaft 35 is adapted to be rotated by the motor 26 and the rotatable speed and the direction of its rotation is controlled by manual operation of the usual gear shift lever 39.

The shaft 35 has suitably secured to its end the sprocket 40 having the belt chain 41

meshing therewith. The chain 41 is operatively meshed with the sprocket 42 fixed to the end 43 of the horizontal shaft 44 rotatably mounted in the bearings 45 in the upwardly extending bosses 46 integral with the base plate 4.

Secured to the end 47 of the shaft 44 is the bevel gear 48 meshing with the bevel gear 49 secured to the end 50 of the horizontal shaft 51 rotatably mounted in the upwardly extending bosses 52 integral with the base plate 4. Secured to the other end 53 of the shaft 51 is the bevel gear 54 meshing with the bevel gear 55 suitably fixed to the lower end of the screw 21.

For the purpose of accomplishing a low gear ratio from the transmission output shaft 30 to mechanism adapted to operate the carriage 11, the relatively small spur gear 56 is fixed to the outer end of the shaft 33 and is meshed with the relatively large gear 57 rotatably mounted upon the shaft 58 suitably fixed in the upwardly extending boss 59 integral with the base plate 4. Integrally formed with the hub 60 on the outer side of the gear 57 is the relatively small gear 61 meshing with the relatively large gear 62 rotatably mounted upon the end of the shaft 33. Integrally formed with the hub 63 of the gear 62 is a sprocket 64 operatively connected with the sprocket 65 by the belt chain 66.

The idler sprocket 67, mounted on the shaft 68 fixed to the boss 69 integral with the base plate 4, meshes with the chain 66 to maintain the chain in operative position.

The sprocket 70 is fixed to the shaft 71 rotatably mounted in the upwardly extending bosses 72 integral with the base plate 4. Rotatably mounted in the spaced apart upwardly extended bosses 73 is the shaft 74 having suitably fixed thereto the sprocket 75 in alignment with the sprocket 70. The belt chain 76 is geared to the sprockets 70 and 75 whereby rotation of the shaft 71 imparts rotatable movement to the shaft 74. Fixed to the end of the shaft 74 is a beveled gear 77 meshing with the beveled gear 78, fixed to the lower end of the screw 24, whereby rotatable movement is imparted to the screw, through the gearing mechanism just explained, by rotation of the shaft 33 operated by the output shaft 30 of the transmission 29, whereby the rotatable speed of the screw 24 may be varied by operation of the gear shift handle 39 of the transmission.

Adjacent the lower screws 21 and 24 are the vertical hollow tubes or supports 79 and 80 having their lower ends suitably fixed in the bushings 80' in the base plate 4. Integral with the upper ends of the tubes 79 and 80 are the internally threaded nuts 81 and 81'. The nuts 81 and 81' are threaded to the lifting screws 82 and 83, respectively, having

their upper ends 84 and 84' fitted in suitable bearings in the top plate 5. Fixed upon the upper ends of the screws 82 and 83 are the collars 85 which engage the lower side 86 of the top plate 5, when the screws travel upwardly, as will be fully explained hereinafter.

Fixed to the upper end 87 of the screw 83 is the gear 88 having integral with its upper side the sprocket gear 89 which is operatively connected with the sprocket gear 90, fixed to the upper end of the screws 82, as by the chain 91.

Fixed in the central portion of the top plate 5 is the vertical pin 92 on which is mounted the idler sprocket gear 93 which meshes with the chain 91 and maintains the chain taut.

The screws 21 and 24 are fitted with the oppositely disposed key ways 94 and 95 which are cut the full length of the screws. Slidably mounted in the key ways 95 are the keys 96 which are secured to the inner surfaces 97 of the hollow upper screws 98 and 99, having fixed in their upper ends the plugs 100 mounted in suitable bearing in the top plate 5. Intermediate the top plate and the upper ends of the screws are the bushings 101.

Rotation is imparted to the upper screws 98 and 99 through the keys 96 which are received in the key ways 95 in the screws 21 and 24.

Keyed to the end 102 of the plug 100 is the gear 103. Mounted in the top plate 5 is the pin 104 on which is pivotally mounted the hub 105 integral with the arm 106 which has fixed in its hub 107 the pin 108 on which is rotatably mounted the gear 109 which meshes with gear 88 and 103 when the arm 106 is locked in the position shown in Fig. 7, whereby rotatable motion is imparted to the screws 82 and 83 by the screw 99, through the mechanism previously explained.

The arm 106 is retained in locked position by the dog 110 which engages the handle 111 which is integral with the hub 105 of the arm 106. The dog 110 is pivotally mounted upon the pin 112 which is fixed in the upwardly extending bosses 113 integral with the upper side of the top plate 5.

The upper ends of the telescopic supports 6 are fixed to the lugs 114 integral with the top plate 5 and have their lower ends slidably received in the holes 7 of the vertical supports 3 which have lower ends received in the studs 115 integral with the base plate 4.

Fixed to the lugs 116 integral with the top plate 5 are the brace rods 117 which extend rearwardly a sufficient distance to clear the mechanism on the rear of the carriage frame and then extend downwardly. The lower ends of the rods 117 are slidably received in the vertical tubes 118 which have their lower ends fixed in the base plate 4. Slidably mounted upon the tubes 118 is the platform 119

119 which is held in position by the screw 120 threaded in the tubes 118.

To raise and lower the telescopic supports 6 rotation of the screw 99 is imparted to the 5 screws 82 and 83 through the gearing mechanism previously explained, whereby the screws 82 and 83 are caused to travel upwardly or downwardly upon the threads in the nuts 81 and 81' integral with the vertical 10 tube 80. After the supports of the frame 2 have reached the desired height of the plastering surface, the idler gear 109 is disengaged from the gear 88 and 103, as shown by dotted lines in Fig. 7.

15 The carriage frame 12 has the internally threaded hub 23, integral with side 14, which is threaded to engage the threads on the tubular screw 99. When the carriage is below the screw 99 the hub 23 is locked to the internally threaded plug 121 by means of the pivotally mounted fingers 122 and 122' which are received in the vertical slots 123 and 123' in the outer side of the plug 121, as shown in Fig. 3.

25 The hubs 124 and 124', of the fingers 122 and 122', are pivotally mounted upon the pins 125 and 125', which are received in the bosses 126 and 126' integral with the outer side of the hub 23.

30 Integral with the upper ends of the fingers 122 and 122' are the bosses 127 and 127' which receive the ends of the springs 128 and 128' which have their opposite ends received upon the bosses 129 and 129' integral with the 35 outer surface of the hub 23.

Integral with the upper end of the plug 121 is the circumferential shoulder 130. The externally threaded circumferential plug 131 is slidably keyed to the screw 24 by the key 40 132 which is received in the key way 94 of the screw 24. The plug is maintained in proper position on the screw 24 by the upper end 133 of the shoulder 130.

When plaster is to be applied to the wall surface, the carriage 11 is lowered to the lowest position on the frame 2. Rotatable movement is applied to the screw 24, through the mechanism previously described, which causes the plug 121 to lift the carriage in an upward direction, as the fingers 122 and 122' lock the plug 121 to the hub 23 of the carriage frame. The carriage is transported in an upward direction by the screw 24 until the plug 131 contacts the lower end of the screw 99 at which point the gear 134, which is slidably keyed to the plug 131, continues upwardly on the screw 99. The hub 23 engages the threads on the plug 131 and travels upwardly until the threads of the hub 23 engage the threads on the screw 99, whereby the carriage is carried upwardly to the uppermost position on the frame, adjacent the top plate 5, by rotation of the screw 99, which is rotated by the screw 24 through the key 96, previously explained.

When the hub 23 engages the upper screw 99 it travels upwardly and the fingers 122 and 122' slide out of the slots 123 of the plug 121, whereby the plug remains in stationary position on the screw 24.

After the carriage has traveled to the desired point on the frame 2, the direction of rotation of the screws 24 and 99 is reversed by shifting the gear shift lever 39, thereby changing the gear reduction in the transmission box 29.

When rotation of the screw 99 is reversed the hub 23 moves downwardly upon the screw 99. When the hub 23 reaches the lower end of the screw 99 the fingers 122 and 122' engage the slots 123 in the plug 121, whereby the carriage continues downwardly upon the screw 24, as by the plug 121 being locked with the hub 23 of the carriage frame by the fingers 122 and 122'. The springs 129 and 129', being under compression, forces the upper ends of the fingers outwardly whereby the lower ends of the fingers are forced inwardly in the slots 123 of the plug 121.

The gear 134 follows the hub 23 and engages the plug 131 which is keyed to the screw 24, whereby rotatable movement is imparted to the gear 134.

The gear 135 is slidably keyed to the screw 98 by the key 136 being received in the key way 137. When the hub 20 of the carriage travels downwardly on the screw 98 the lower end 138 of the hub 20 engages the shoulder 139 on the bushing 140, which is keyed to the screw 21 by the key 141. The gear 135 follows the hub 20 in its downward travel and the key 136 is received in the key way 142 in the outer face of the bushing 140, whereby rotation of the screw 21 is imparted to the gear 135.

For the purpose of providing convenient means for manually positioning a plastering device adjacent a vertical surface of wall to be plastered, the ring 144, integral with the lower surface of the base plate 4, is movably received in the circular groove 145 in the platform 146 having the castors 147 suitably mounted in its lower surface. For the purpose of maintaining the ring 144 in spaced apart relation with the walls 148 of the groove 145, the downwardly extending boss 149, integral with the lower surface of the base plate 4, is received in the centrally disposed recess 150 of the platform 146.

When the plastering device is properly positioned, with respect to the walled surface to be plastered, the horizontal screws 151, threaded in the platform 146, are screwed inwardly with their inner ends 152 in frictional engagement with the outer side of the ring 144, whereby the base plate 4 is maintained in fixed position with relation to the platform 146.

The platform 119 is for the purpose of enabling the operator of the plastering machine 130

to gain access conveniently to the manually operative lever 111 for the purpose of engaging and disengaging the gear 109 with the gears 88 and 103.

5 As explained in my co-pending applications, Serial Nos. 306,487 and 321,378 the arms 153 extend inwardly from the sides 13 and 14 of the carriage. The plaster or other plastic material hopper 154 is secured to the arms.

10 The front roller 155 is mounted upon the shaft 156 having its ends rotatably mounted in bearings in the sides 13 and 14 of the carriage frame. The rear roller 157 is mounted upon the shaft 158 having its ends rotatably mounted in bearings in arms 159 of the carriage frame 12. The belts 160, mounted upon the rollers 155 and 157 convey the plaster from the centrally disposed circumferential 15 groove 95 therein in which is mounted the hopper 154 outwardly of the frame 2.

15 Keyed to the screw 98 is the beveled gear 135 meshing with the bevel gear 161 fixed to the end of the horizontal shaft 162 rotatably mounted in bearings in the webs integral with the struts 17 and 18. To the end of the shaft 162 is fixed the sprocket 163 having meshed therewith a belt chain (not shown) which is meshed with a sprocket mounted upon the 20 rear shaft 158, whereby rotation of the output shaft 35 of the transmission is adapted through the mechanism previously explained, to impart rotatable movement to the screw 21 which in turn imparts rotatable movement to the rear roller 157, through the mechanism just previously explained.

25 The plaster dropped from the front roller 155 is pressed upon the wall by the pressing mechanism 164, fully explained in my co-pending application Serial No. 306,487.

30 The mechanism 165, for smoothing the plaster, also is fully explained in the above mentioned co-pending applications.

35 An advantage of the invention is that the height of the frame of the plastering machine may be adjusted to permit the carriage to travel from the floor to the ceiling irrespective of the height of said ceiling.

40 Furthermore, the machine may be adjusted with the top plate 5 adjacent the upper ends of the tubular supports 3, when a room having a low ceiling is being plastered whereby, since the supports 6 are slidably received in the supports 3, the machine in its reduced size is no more bulky nor difficult to operate than if the machine were made especially for the purpose of plastering rooms having low ceilings.

45 Various slight changes might be made in the general form and arrangement of parts described without departing from my invention, and hence I do not limit myself to the precise details set forth, but consider myself at liberty to make changes when such

changes and alterations fall within the spirit and scope of the appended and final claims.

What I claim as new and desire to secure by Letters Patent is:

1. In a plastering device, a frame adapted to be positioned adjacent a surface and comprising a plurality of spaced apart lower tubes having their ends fixed in said base, a plurality of spaced apart upper tubes slidably mounted in said first mentioned tubes, a top 70 plate, the upper ends of said upper tubes being fixed in said top plate, a carriage slideable on said upper and lower tubes, means for elevating and lowering said carriage on said frame comprising a lower vertical screw, an 75 upper vertical screw having its upper end rotatably connected with said top plate, the upper end of said lower screw being slidably received in said upper screw and keyed thereto, means to rotate said lower screw, means 80 fixed to said carriage and operatively connected with said upper and lower screws whereby rotation of said lower screw causes said last mentioned means to travel upwardly and downwardly of said upper and lower 85 screws, means to convey plaster from said carriage outwardly of said frame, means to spread said plaster on said surface, means to adjust the height of said top plate from said base comprising a lifting screw having its 90 upper end connected with said top plate, means operatively connecting said upper screw with said lifting screw whereby rotatable movement is imparted to said lifting screw, a vertical support having its lower 95 end fixed to said base, an internally threaded 100 nut integral with the upper end of said support, the lower end of said lifting screw being threaded to said nut, and manually operative means to disconnect operative connection of said upper screw with said lifting screw.

2. In a plastering device, a vertical frame adapted to be positioned adjacent a vertical surface and comprising a base, a plurality of spaced apart lower vertical tubes having their lower ends fixed in said base, a plurality of spaced apart upper tubes having their lower ends slidably mounted in said lower tubes, a top plate, the upper ends of said upper tubes being fixed in said top plate, a carriage vertically slideable on said upper and lower tubes, means for elevating and lowering said carriage comprising a motor on said base, a lower vertical screw having its lower end rotatably mounted in said base, an upper vertical screw having its upper end rotatably connected with said top plate, the upper end of said lower screw being slidably received in said upper screw and keyed thereto, means operatively connected with said motor and said lower screw whereby said lower screw and said upper screws are rotated, and means fixed to said carriage and operatively connected with said upper and lower 130

- screws whereby rotation of said lower screw causes said last mentioned means to travel upwardly and downwardly of said upper and lower screws, a supply hopper mounted on 5 said carriage frame, means operated by said motor adapted to convey plaster from said hopper outwardly of said frame, means to spread said plaster onto said vertical surface, means to adjust the height of said top 10 plate from said base, to conform with the height of said vertical surface, comprising a vertical lifting screw having its upper end rotatably mounted in said top plate, manually operative means to operatively connect said 15 upper screw with said lifting screw whereby rotatable movement is imparted to said lifting screw, a tubular vertical support having its lower end fixed in said base, and an internally threaded nut integral with the 20 upper end of said tubular support, the lower end of said lifting screw being threaded to said nut.
3. In a plastering device, a vertical frame adapted to be positioned adjacent a vertical 25 surface and comprising a base, a plurality of spaced apart lower vertical tubes having their lower ends fixed in said base, a plurality of spaced apart upper tubes having their lower ends slidably mounted in said lower tubes, a 30 top plate, the upper ends of said upper tubes being fixed in said top plate, a carriage vertically slidable on said upper and lower tubes, means for elevating and lowering said carriage comprising a motor on said base, a lower vertical screw having its lower end rotatably mounted in said base, an upper vertical screw having its upper end rotatably connected with said top plate, the upper end of 35 said lower screw being slidably received in said upper screw and keyed thereto, means operatively connected with said motor and said lower screw whereby said lower screw and said upper screw are rotated, and means fixed to said carriage and operatively connected with said upper and lower screws whereby rotation of said lower screw causes 40 said last mentioned means to travel upwardly and downwardly of said upper and lower screws, means operated by said motor adapted to convey plaster from said carriage outwardly of said frame, means to spread said plaster on said vertical surface, means to adjust the height of 45 said top plate from said base comprising a lifting screw having its upper end connected with said top plate, means operatively connecting said upper screw and said lifting screw whereby rotatable movement is imparted to said lifting 50 screw, a vertical support having its lower end fixed to said base, an internally threaded nut integral with the upper end of said tubular support, the lower end of said lifting screw being threaded to said nut, and manually operative means to disconnect operative con- 55 nection of said upper screw with said lifting screw.
4. In a plastering device, a frame adapted to be positioned adjacent a vertical surface and comprising a base, a plurality of spaced apart lower tubes having their lower ends fixed in said base, a plurality of spaced apart upper tubes slidably mounted in said lower tubes, a carriage vertically slidable on said upper and lower tubes, means for elevating and lowering said carriage comprising a lower vertical screw means to rotate said screw, an upper vertical screw, the upper end of said lower screw being slidably received in said upper screw and keyed thereto, means connected with said carriage and operatively connected with said upper and lower screw whereby rotation of said screws causes said last mentioned means to travel upwardly and downwardly of said frame, means operated to convey plaster outwardly of said frame, means to spread said plaster on said vertical surface, and means to adjust the height of said frame comprising a lifting screw having its upper end connected with said upper tubes, means operatively connecting said upper screw with said lifting screw whereby rotatable movement is imparted to said lifting screw. 60
5. In a plastering device, a frame adapted to be positioned adjacent a vertical surface and comprising a base, a plurality of spaced apart lower tubes having their lower ends fixed in said base, a plurality of spaced apart upper tubes slidably mounted in said lower tubes, a carriage vertically slidable on said upper and lower tubes, means for elevating and lowering said carriage comprising a lower vertical screw means to rotate said screw, an upper vertical screw, the upper end of said lower screw being slidably received in said upper screw and keyed thereto, means connected with said carriage and operatively connected with said upper and lower screws whereby rotation of said screws causes said last mentioned means to travel upwardly and downwardly of said frame, means operated to convey plaster outwardly of said frame, means to spread said plaster on said vertical surface, and means to adjust the height of said frame. 65
6. In a plastering device, a frame, comprising a plurality of spaced apart lower supports, a plurality of spaced apart upper supports slidable on said lower supports, a carriage vertically slidable on said frame, said carriage and said frame being adapted to be positioned adjacent a vertical surface, means to convey plaster from said carriage outwardly of said frame, means for elevating and lowering said carriage on said frame, a vertical lifting screw having operative connection with said upper supports whereby rotation of said lifting screw imparts ver- 70 75 80 85 90 95 100 105 110 115 120 125 130

tical movement to said upper support, and means to rotate said lifting screw.

7. In a device of the character described, a vertical frame, a plurality of spaced apart lower vertical tubes, a plurality of spaced apart upper tubes having their lower ends slidable in said upper tubes, a top plate fixed to the upper ends of said upper tubes, a carriage vertically slidable on said frame, means to adjust said carriage to operating position adjacent a vertical surface, means to convey plaster from said carriage outwardly of said frame, means for elevating and lowering said carriage on said first mentioned frame, comprising a lower vertical screw, an upper tubular screw, the upper end of said lower screw being slidably received in said upper screw and keyed thereto, means to rotate said screws, and means fixed to said carriage threaded to said screws, a gear connected with the upper end of said upper screw, a vertical lifting screw having its upper end rotatably mounted in said top plate, a gear fixed to said lifting screw, a tubular vertical support and an internally threaded nut integral with the upper end of said tubular support, the lower end of said lifting screw being threaded to said nut whereby rotatable movement of said lifting screw imparts vertical movement to said top plate and manually operative means to operatively connect said gears.

8. In a device of the character described, a vertical frame consisting of a base, a plurality of spaced apart lower vertical tubes having their lower ends fixed to said base, a plurality of spaced apart upper tubes with their lower ends slidable in said upper tubes, a top plate fixed to the upper ends of said upper tubes, a carriage vertically slidable on said vertical frame, means to adjust said carriage to operating position adjacent a vertical surface, means for retaining on said first mentioned frame a motor, means operated by said motor adapted to convey plaster from said carriage outwardly of said frame, means for elevating and lowering said carriage on said frame, said last mentioned means comprising a lower vertical screw having its lower end rotatably mounted in said base, means connected with said motor to rotate said lower screw, an upper tubular screw, the upper end of said lower screw being slidably received in said upper screw and keyed thereto, and means connected with said carriage and said upper and lower screws whereby rotation of said screws impart vertical movement to said carriage, a plug fixed in the upper end of said upper screw, said plug rotatably mounted in said upper plate and having its upper end projecting through said top plate, a gear fixed to the upper end of said plug, a vertical lifting screw having its upper end rotatably mounted in said top plate, a gear fixed to said

lifting screw, manually operative means to disconnect and operatively connect said gears, a tubular vertical support having its lower end fixed in said base, an internally threaded nut integral with the upper end of said tubular support, the lower end of said lifting screw being threaded to said nut whereby rotatable movement of said lower screw imparts rotatable movement to said lifting screw, means fixed to said lifting screw adapted to force said top plate upwardly when said lifting screw moves upwardly.

9. In a device of the character described, a vertical frame adapted to be positioned adjacent a vertical surface and comprising a base, a plurality of spaced apart lower vertical tubes having their lower ends fixed in said base, a plurality of spaced apart upper tubes slidably mounted in said lower tubes, a top plate, the upper ends of said upper tubes being fixed in said top plate, a carriage vertically slidable on said upper and lower tubes, means for elevating and lowering said carriage comprising a motor on said base, a lower vertical screw having its lower end rotatably mounted in said base, an upper vertical screw having its upper end rotatably connected with said top plate, the upper end of said lower screw being slidably received in said upper screw and keyed thereto, means operatively connected with said motor and said lower screw whereby said lower screw and said upper screw are rotated, and means fixed to said carriage and operatively connected with said upper and lower screws whereby rotation of said lower screw causes said last mentioned means to travel upwardly and downwardly of said upper and lower screws, a supply hopper mounted on said carriage frame, means operated by said lower screw adapted to convey plaster from said hopper outwardly of said frame, means to spread said plaster onto said vertical surface, means to adjust the height of said top plate from said base comprising a vertical lifting screw having its upper end rotatably mounted in said top plate, mechanism connected with said upper screw to impart rotatable movement to said lifting screw, manually operative means to disconnect and operatively connect said mechanism with said lifting screw, a tubular vertical support having its lower end fixed to said base, and an integrally threaded nut integral with the upper end of said tubular support, the lower end of said lifting screw being threaded to said nut.

10. In a device of the character described, a vertical frame consisting of a base, a plurality of spaced apart lower vertical tubes having their lower ends fixed to said base, a plurality of spaced apart upper tubes having their lower ends slidable in said upper tubes, a top plate fixed to the upper ends of said upper tubes, a carriage vertically slidable on

said frame, means to adjust said carriage frame to operating position adjacent a vertical surface, means for retaining on said frame a motor, means operatively connected with said motor to operate said carriage frame, a supply hopper mounted on said carriage frame, means operated by said motor adapted to convey plaster from said hopper outwardly of said frame, means for elevating and lowering said carriage on said first mentioned frame comprising a lower vertical screw having its lower end rotatably mounted in said base, means operatively connecting said motor with said lower screw, an upper tubular screw, the upper end of said lower screw being slidably received in said upper screw and keyed thereto, a plug fixed in the upper end of said upper screw, said plug rotatably mounted in said top plate and having its upper end projecting through said top plate, a gear fixed to the upper end of said plug, a vertical lifting screw having its upper end rotatably mounted in said top plate, a gear fixed to said lifting screw, a tubular vertical support having its lower end fixed in said base, an internally threaded nut integral with the upper end of said tubular support, the lower end of said lifting screw being threaded to said nut whereby rotatable movement of said lifting screw imparts vertical movement to said top plate and manually operative means to connect and disconnect said gears.

ENRICO MORELLI.
